UNITED STATES PATENT OFFICE.

ALEXANDER FAIRFIELD, OF HARRISVILLE, NEW YORK, ASSIGNOR OF ONE-HALF TO
JOSEPH B. WEEKS, OF HARRISVILLE, NEW YORK.

APPARATUS FOR TAPPING WATER-MAINS UNDER PRESSURE.

1,081,223.

Specification of Letters Patent.

Patented Dec. 9, 1913.

Application filed February 6, 1913. Serial No. 746,661.

To all whom it may concern:

Be it known that I, ALEXANDER FAIRFIELD, a citizen of the United States, residing at Harrisville, in the county of Lewis and 5 State of New York, have invented certain new and useful Improvements in Apparatus for Tapping Water-Mains Under Pressure; and I do hereby declare the following to be a full, clear, and exact description of 10 the invention, such as will enable others skilled in the art to which it appertains to make and use the same, reference being had to the accompanying drawings, and to the letters and figures of reference marked 15 thereon, which form a part of this specification.

This invention relates to new and useful improvements in apparatus for tapping mains containing liquid under pressure and 20 comprises a simple and efficient apparatus of this nature having various details of construction and combinations and arrangements of parts which will be hereinafter fully described, shown in the accompanying 25 drawings and then specifically defined in the appended claims.

I illustrate my invention in the accompanying drawings, in which:—

Figure 1 is a central vertical sectional view through the apparatus shown as applied to a main, the latter being in cross section. Fig. 2 is an enlarged detail section of a part of the apparatus. Fig. 3 is a detail sectional view through the valve 30 clamping and holding device, and Fig. 4 is a sectional view on line 4—4 of Fig. 1.

Reference now being had to the details of the drawings by letter, A designates a yoke adapted to be held about a main B in 40 any suitable manner, as by means of the clamping member B' which is held to the flanges of the yoke by means of the bolts C, shown in dotted lines in the drawings.

A suitable housing, designated by letter 45 D, has flanges D' which are held by means of the screws D² to the flanges of the yoke A, a suitable packing being interposed between said housing and the flange in order to make a tight joint. One end wall of the 50 housing D is apertured as at E to register with an opening in the yoke A and the opposite wall is apertured as at F for the reception of the socket end G of the drill 55 chuck H having a hollow shank portion. Said chuck H has a beveled shoulder H'

adapted to engage a shoulder I formed in the lateral extension or sleeve D³ of the housing D, thereby limiting the movement of said chuck in one direction. The circumference of the extension D³ is threaded as 60 at d for the reception of the sleeve J which has a head J' interiorly threaded and between which sleeve J and the extension D³ a suitable packing K is interposed to make a tight joint. The circumference of the 65 sleeve J is threaded as at J² and is adapted to receive thereon the feeding shell L interiorly threaded and engaging the threads J². Said shell L has cut away portions L' in order to give access to the interior thereof 70 for the purpose of adjusting the set screws N which engage threaded apertures in the collar N', which latter is adapted to be held in different adjusted positions upon the circumference of the chuck H and within the 75 member L.

A ratchet collar M, interiorly threaded, engages threads M' upon the circumference of the chuck H and has ratchet teeth M² formed about the circumference thereof and 80 which are adapted to be engaged by a pawl O having a stem O' movable within the slot O² of the handle P, a spring O³ serving to normally hold the pawl in engagement with the teeth M². A jam nut Q is mounted 85 upon a threaded portion of the circumference of the chuck H and bears against the ratchet collar and serves to hold the handle P upon the circumference of the ratchet collar M.

Mounted to have a longitudinal play within the chuck H is a tube R, circumferentially threaded as at R' for the reception of the threaded jam wheel R² which may be turned against the end of the collar M for the purpose of holding the same against the nut Q. A hand wheel R³ is keyed to one end of the tube R and serves as means for rotating the same. The inner end of the tube R is squared as at R⁴ and is adapted to engage a similar angular outlined socket R⁵ formed in the adjacent end of the shank of the drill R⁶, an enlarged view of which is shown in Fig. 2 of the drawings. Said drill has tapping threads R⁹ which, after 95 the hole is drilled, are adapted to form the threads B⁵ in the marginal edge of the drilled opening B⁶.

Mounted to have a longitudinal play within the tube R is a rod T having a head T' 100

105

110

at its outer end and between which latter and a shoulder T^2 upon the rod a coiled spring T^3 is mounted and serves to normally hold the rod T at its farthest outer limit 5 in one direction.

Fitted within the hollow boss S which is integral with the housing D is an open-ended shell S' , and S^2 designates a packing gland fitted to the threaded circumference 10 of the boss S , making a tight joint intermediate the shell S and said boss. A shaft S^4 is mounted to have a longitudinal movement within the shell S' and passes through a collar S^5 which is interiorly threaded and 15 engaging a threaded portion S^6 of the shell S' and a suitable packing S^7 intermediate the collar and shell form a tight joint. An operating wheel S^7 is mounted upon the threaded portion S^8 of the shaft S^4 and is 20 adapted to bear against the collar S^5 whereby a longitudinal movement may be imparted to the shaft S^4 when the wheel is turned in one direction.

Pivotedly mounted upon a pin W carried 25 by the shaft S^4 are the jaws W' , shown clearly in Fig. 3 of the drawings, and which are concaved and adapted to engage and hold a valve casing X to be inserted in the main after the latter has been tapped. A 30 pin W^2 is supported by the shell S' and against which the two jaws are adapted to contact when an inner thrust is imparted to the shaft S^4 , thereby spreading the jaws to receive the valve in the manner shown in 35 Fig. 3.

Fastened to the housing D is a rack D^5 having a laterally extending arm D^6 surrounding the shell S' and a suitable feather D^7 upon the shell passes through the aperture in the extension D^6 and serves to hold 40 the shell from turning. A shaft V is journaled in said lateral extension D^6 and has a hand wheel V' fixed thereto and also a ratchet wheel V^2 , the teeth of which are in 45 mesh with the teeth of the rack bar D^8 integral with the shell S' .

The operation of my invention will be readily understood and is as follows:—The housing is clamped by the means shown 50 about the main B in any suitable manner, the stuffing box S^2 removed, the valve gripped and held by the jaws W' and the shaft S^4 moved outward in order that the valve will be positioned as shown in Fig. 1 55 of the drawings, in readiness to be advanced to the position to be inserted in the main after the same has been tapped. The drill is inserted in the end of the chuck H , having threaded connection therewith, and the shell 60 with the drill is rotated through the lever P having a pawl thereon, which engages the teeth of the ratchet collar. By the turning of the shell L by hand, the end thereof will contact with the collar N' fixed in any 65 adjustable position within the shell L ,

thereby causing a forward feeding movement to the drill. The hole being tapped in the main, the drill may be removed from the shell with which it has threaded connection during the drilling operation 70 through the medium of the tube R which, when rotated in one direction, will cause the inner squared end of the tube R to unscrew the shank portion of the drill from its socket in the end of the chuck H and, when 75 thus disconnected, the drill may be pushed from over the inner end of the tube R by inserting any object against the head T' of the rod T , thus causing an inner longitudinal movement to be imparted to the same 80 and, when pressure is relieved from the head T' , the latter will return to its normal position which is that shown in Fig. 1. The hole having been tapped in the main, the valve held by the jaws W' may be thrown 85 down to alinement with the drilled aperture by the manipulation of the wheel V' . When the threaded projections of the valve come in alinement with the chuck H and the aperture which has been tapped, the chuck 90 H may be driven forward by the manipulation of the shell L , causing one of the threaded projections of the valve to engage the threads in the wall of the tapped aperture. After the circumferentially threaded 95 projection Y^2 of the valve Y' is engaged by the threads on the wall of the socket at the end of the chuck H , the threaded projections of the valve casing will be in alinement with the tapped opening in the main, 100 after which the jaws are released from the valve by the manipulation of the shell S^5 and, when thrown back from engagement with the valve, they may be withdrawn by the rotation of the wheel V' , causing the 105 ratchet wheel to engage and impart a longitudinal movement to the shell S' . The valve may then be turned so that the projecting portion Y^2 of the shell is in threaded engagement with the threads in the hole 110 which has been tapped in the main after which the chuck is released from the valve. This having been accomplished, the housing and the parts of the apparatus may be removed from the main, which has been 115 tapped, and the valves inserted therein without interference with the liquid pressure within the main.

What I claim to be new is:—

1. An apparatus for tapping mains comprising a housing adapted to be clamped to a main, a longitudinally movable shell mounted to move within a suitably packed boss projecting from the housing, a shaft movable within said shell, jaws pivotally connected to said shaft and adapted to hold a valve, means for imparting a longitudinal movement to the shell, a drill chuck movable within suitable bearings within said housing and at right angles to said shaft, a drill 120

in said chuck, means for rotating the latter, and feeding mechanism for the chuck, as set forth.

2. An apparatus for tapping mains comprising a housing adapted to be clamped to a main, a longitudinally movable shell mounted to move within a suitably packed boss projecting from the housing, a shaft movable within said shell, jaws pivotally connected to said shaft and adapted to hold a valve, means for imparting a longitudinal movement to the shell, a drill chuck movable within suitable bearings within said housing and at right angles to said shaft, a drill

in said chuck means for rotating said chuck, 15 an open-ended tube mounted movable within said drill chuck, the inner end of said tube adapted to engage a recess formed in the inner end of the shank portion of the drill, and a hand wheel fitted to said tube, as set 20 forth.

In testimony whereof I hereunto affixed my signature in the presence of two witnesses.

ALEXANDER FAIRFIELD.
